UNITED STATES PATENT OFFICE.

THOMAS BRADY, OF EAST ORANGE, NEW JERSEY, ASSIGNEE, BY MESNE ASSIGNMENTS, TO OTIS ELEVATOR COMPANY, OF NEW YORK, N. Y., A CORPORATION OF NEW JERSEY.

DOOR CLOSER.

Application filed February 15, 1923. Serial No. 619,231.

This invention relates to door closers and, particularly, to closers such as are used for elevator hatchway doors.

It is common practice at the present time to manufacture door closers of different sizes to fit the various sizes of doors. This practice involves expense since it necessitates carrying in stock several sizes of links and operating parts. Furthermore, it often happens that on installation further fitting and adjusting is necessary and this still further increases the cost of the installation.

This invention has for its object to provide a standard closure device so constructed and arranged that it can be readily adjusted and effectively used with a plurality of different sizes of door installations.

Another object of the invention is to provide a door actuating and checking or cushioning mechanism so constructed and arranged that it will operate effectively, will be durable and will not be subject to leakage and other effects.

Another object of the invention is to provide a door closure so constructed as to be capable of adjustment in a manner to properly align the operating links so as to reduce to a minimum the friction between the co-acting parts.

Another object of the invention is to provide a device of the character described that is simple in construction, efficient in operation and inexpensive to manufacture.

Further objects of the invention will appear from the following specification taken in connection with the drawings, which form a part of this application, and in which:

Fig. 1 is an elevational view of a door installation showing operating and checking mechanism constructed in accordance with the invention.

Fig. 2 is a transverse sectional view taken substantially on line 2—2 of Fig. 1.

Fig. 3 is a sectional elevation similar to Fig. 2, but showing the door section in open position.

Fig. 4 is a sectional elevation illustrating the construction of the actuating and cushioning means for the door closure mechanism.

Fig. 5 is a detail elevational view on an enlarged scale showing the pivotal connec-

tion between one of the operating links and one of the door sections.

Fig. 6 is an elevational view taken at right angles to Fig. 5.

Fig. 7 is an elevational view similar to Fig. 5, but showing the pivotal connection between adjacent links.

Fig. 8 is a transverse sectional elevation taken substantially on line 8—8 of Fig. 7.

Fig. 9 is an elevational view of the handle.

Fig. 10 is an end view taken at right angles to Fig. 9.

Fig. 11 is a detail sectional elevation showing the roller mounting for the door sections.

Fig. 12 is a detail sectional elevation showing the guiding means for the lower ends of the door sections.

Fig. 13 is a transverse sectional elevation of a cylinder taken substantially on line 13—13 of Fig. 4.

Fig. 14 is a sectional elevation similar to Fig. 13 but taken substantially on line 14—14 of Fig. 4.

Fig. 15 is an elevational view on an enlarged scale showing the construction of the adjustable joints between the sections of the end link which is pivoted to the fixed abutment, and

Fig. 16 is a top plan view of the construction shown in Fig. 15.

The invention briefly described consists of means for operating a plurality of sliding door sections and this means comprises links pivotally connected to the door sections and to each other, one of the end links being pivoted on a fixed pivot. In order to adapt the device for use in connection with the different sizes of door sections and door installations, means is provided for adjustably connecting the links to the door sections and for adjustably connecting the links to each other. The end link which is connected to a fixed pivot is made sectional and the sections are adjustably connected so that the links may be properly aligned with reference to the doors, as, in order to avoid undue friction, the links should be disposed in planes parallel to the planes of the door sections.

The invention also includes actuating and cushioning means for operating the links. The actuating means preferably includes a tension spring connected at one end to a rod

- which is adjustably connected to the end link and the rod is slidably mounted in a cylinder and has mounted on its end a piston operating in the cylinder. The cylinder is preferably pivotally connected to a fixed pivot. The actuating means includes a piston and cylinder and a by-pass in the cylinder wall for conducting the fluid, such as oil, around the piston as the piston is moving downwardly in the cylinder and approaches the bottom of the cylinder. A passage through the piston is provided for permitting the fluid to pass downwardly as the piston is raised and this passage is controlled by a contact valve. Various adjustments between the coating parts will be described in the detailed description which follows and in which further details of the invention will be set forth.
- 10 In the embodiment of the invention shown the door comprises a stationary section 20 and slidable sections 21 and 22, these two latter sections being adapted to move into overlapping position with the stationary section 20 as shown in Fig. 3.
- 15 The door sections may be mounted in any desired manner and in the particular form of the invention illustrated each of the sections 21 and 22 is provided with rollers 23 mounted on a rail 24 disposed above the hatchway opening. The door sections are also guided by means of downwardly extending webs 25 (see Fig. 12) which are disposed in slots 26 formed in a plate 27 mounted at the bottom of the hatchway opening.
- 20 Operating means for the slidable door sections comprises a plurality of links A, B and C. The link A is adjustably mounted in a clamp 30 which is pivoted at 31 on a plate 32 secured to the door section 22. The construction of the clamp 30 is illustrated in detail in Figs. 5 and 6 and from these figures it will be seen that the clamp comprises parallel plates 33 and 34 adapted to receive between them the end portion of the link A and when this link has been properly adjusted in the clamp, the clamp is tightened by means of screws 35. A lug 36 extends upwardly from the clamp and is pivoted as before stated at 31 to the plate 32.
- 25 The link A is pivotally connected to the link B through an adjustable clamp 40 illustrated in detail in Figs. 7 and 8. This clamp comprises parallel plates 41 and 42 adapted to receive between them one end portion of the link B and screws 43 secure this link portion in its adjusted position. The clamp 40 is connected by a pivot pin 44 to the link A.
- 30 The link B is pivotally connected intermediate its ends to the door section 21 in the following manner. A bracket 50 is preferably adjustably secured to one side edge of the section 21, this bracket having a plate 51 formed thereon. The link B is ad-

justably connected to the plate 51 by means of a clamp 52 exactly similar in construction to the clamp 30 already described and, therefore, the details of this clamp will not be specifically explained. The link B is pivotally connected to the free end of the link C by means of a clamp 55 exactly similar in construction to the clamp 40 already described.

35 The link C comprises a plurality of sections which are designated for convenience as C', C² and C³. The section C³ is pivotally mounted on a horizontal pivot 60 formed in a bracket 61. The bracket 61 is secured to a vertically disposed plate or strip 62 secured at 63 to one side wall of the elevator hatchway.

40 Since dimensions vary and the construction of the hatchway is not uniform, it is desirable to provide means for adjustably connecting the sections C', C² and C³ of the end link C to each other for the purpose of properly alining the links A, B and C as these links should be disposed in planes parallel to the planes of the door sections in order to operate effectively and with a minimum amount of friction. These adjustable connections are particularly illustrated in Figs. 15 and 16 and may be described as follows. The section C' of the end link has secured to one end an adjustable clamp 65 similar in construction to the clamps already described. The clamp 65, however, has formed thereon an ear 66 and the section C² has formed on one end parallel ears 67 so spaced apart as to receive the ear 66 as shown in Figs. 1 and 15. Each of these ears has an opening formed therethrough and the opening is preferably star-shaped or provided with radial notches 68. These openings are adapted to register when the ears 66 and 67 are placed in overlapping relation and the clamp 65 is connected to the end of the section C² by means of a bolt 70. This bolt is also star-shaped in section and properly dimensioned to fit within the openings in the ears 66 and 67. The bolt 70 has reduced threaded extensions 71 and 72 and on these extensions are mounted nuts 73. In order to adjust the sections C' and C², the bolt 70, which connects these parts, is removed and the link C is properly alined with reference to the links A and B and with reference to the planes of the door sections.

45 The section C² is then angled to the desired position and the bolt 70 is inserted and thereafter the nuts are tightened securely clampng these parts in adjusted position. A similar joint is formed between the sections C² and C³, this joint being indicated by the reference character 75 and as this joint is exactly similar to that already described, no further explanation thereof is deemed necessary.

50 From the foregoing description, it will be

seen that a wide range of adjustment between the sections C', C² and C³ can be obtained and that these sections can be properly adjusted to aline the link C with the remaining links of the door sections.

5 A handle 80 is adjustably secured to the operative links and in the particular embodiment of the invention shown, this handle is connected to an end of the link B disposed beyond the pivotal connection between the links A and B. The construction of this handle is particularly illustrated in Figs. 9 and 10 wherein it will be seen that the handle comprises parallel plates 81 and 82 which receive between them the end of the link B. Screws 83 are provided for clamping these plates to the link. A hand grip or extension 84 is formed on the plate 81. It will, of course, be understood that if the operator 20 desires the handle can be secured to the links in another position as, for instance, to the link B on the opposite side of the pivotal connection between the links A and B. The position of the handle will be determined 25 by the size and reach of the operator.

The actuating and cushioning mechanism for the door closure will now be described. This mechanism comprises a rod 90 adjustably connected by a socket 91 threaded to 30 the upper end of the rod to an extension 92 formed on the section C³ of the link C. The socket 91 is pivoted at 93 to the extension 92.

The rod 90 extends downwardly into a cylinder 94, the lower end of which is closed 35 by a plug 95 and this plug is pivoted at 96 on a bracket 97 secured to the strip 62. A gasket 98 is preferably inserted between a shoulder 99 formed on the plug and the lower end of the cylinder to prevent leakage.

40 The link operating mechanism comprises a sleeve 100 having a nut 101 threaded on its upper end and secured thereto in adjusted position by set screws 102. The nut 101 is threaded as shown at 103 on the upper portion 45 of the rod 90. The lower end of the sleeve 100 is bell-shaped or flared outwardly as shown at 104 and has mounted thereon a bell-shaped washer 105. A tension spring 106 is mounted as shown in Fig. 4 on the outer surface of the washer 105 and the lower end of the spring is secured by means 50 of a plurality of hooked-shaped bolts 107 to a collar 108 which in turn is secured by a plurality of set screws 109 which engage in recesses 109^A formed in the outer surface of 55 the cylinder 94. From the foregoing description it will be seen that as the links A, B and C are moved by the operator to the dotted line position shown in Fig. 1, the upward movement of the link C and of the end section C³ of this link will draw the rod 90 60 upwardly thereby placing the spring 106 under tension since the opposite end of the spring 106 is securely clamped to the cylinder 65 and the cylinder is pivotally mounted on

the fixed pivot 96. The tension of the spring can be adjusted by turning the nut 101 since this will cause the sleeve 100 to move longitudinally on the rod 90 and within the washer 105.

70

The cushioning means comprises a piston 110 pivoted at 111 to the lower end of the rod 90 and disposed within the cylinder 94. The lower end portion of the cylinder is adapted to receive fluid, such as oil, and a filling opening 112 is provided, this opening being closed by a plug 113. Attention is called to the fact that this opening is disposed at the proper level to insure the requisite amount of fluid in the cylinder and to effectively prevent an oversupply of fluid from being inserted since the cylinder cannot be filled above the opening.

80

The piston 110 is provided with a passage 114 extending therethrough from the top to the bottom and at the bottom of the piston the passage is enlarged as shown at 115 and in this enlargement there is mounted a ball check valve 116. This check valve opens 90 downwardly and closes upwardly and a pin 117 is provided for supporting the ball when the piston is traveling upwardly. When the piston moves upwardly in the cylinder the fluid will pass downwardly through the passage 114 since the check valve is open. When the piston moves downwardly, however, the check valve will close and the fluid cannot pass through the piston.

95

One wall of the cylinder 94 is provided with a by-pass 120 communicating with the bottom of the cylinder through a port 121 and communicating with the cylinder at a point above the bottom through a port 122. The size of the opening through the port 122 100 can be regulated by an adjustable needle valve 123.

100

The lower end of the piston is preferably beveled as shown at 124.

110

When the piston travels upwardly it is desirable that the fluid shall pass downwardly therethrough or to the lower portion of the cylinder with as little impedance as possible. In order to effect this ready passage of the fluid, the upper portion of the cylinder is fluted or provided with a plurality of longitudinally extending grooves 125 but the lower portion of the cylinder through which the piston travels during the cushioning operation is cylindrical and has no grooves therein.

115

In order to guide the rod 90 through the upper end of the cylinder, an extension 130 is formed thereon, this extension having a chamber 131 therein communicating through a passage 132 with the upper portion of the cylinder and having an air vent 133 at the upper end thereof. Attention is called to the fact that the passage 132 and air vent 133 are disposed on opposite sides of the rod 90 for the purpose of preventing any

125

120

130

undue leakage of oil through the chamber 131 from the cylinder 94.

A casing 135 is secured at one end to the collar 108 and at its opposite end to a collar 136 mounted on the sleeve 100. This casing encloses the spring 106. The collar 136 is provided with an air vent 137 at its upper end.

As shown in Fig. 4 the by-pass 120 is formed by drilling into one end of the cylinder wall and this wall is formed with an enlargement or is of increased thickness on the side where the by-pass is located. The open end of the drilled hole is closed by a screw 140 and a gasket 141 is preferably inserted between the screw and the end of the cylinder wall.

The door closure mechanism is installed and operated in the following manner. The door sections are first moved to the closed position shown in Fig. 1. The links A, B and C are then pivotally connected to each other and pivoted to the door sections in such a position that they will be properly aligned with reference to each other and to the door sections. The sections of the link C, namely, C¹, C² and C³, are then relatively adjusted with reference to each other and pivotally connected at 60 to the bracket 61 in such a manner that the links A, B and C will be disposed parallel to each other and to the door sections. The operating and cushioning means is then secured to the section C³ of the link C at the pivot point 93 and the opposite end of this means is pivoted at 96 to the bracket 97. Before the ends of the actuating and cushioning means are connected to the extension 92 and bracket 97 respectively, the socket 91 will be adjusted to properly position the rod 90 and the nut 101 will be turned on the rod 90 to place the desired tension on the spring 106. When these parts have been adjusted in the manner described and the handle 80 has been mounted in the desired position on the links, the mechanism may be operated as follows.

Assuming that the doors are in closed position, the operator will pull downwardly on the handle 80 thereby causing the door sections 21 and 22 to slide to the position shown in Fig. 3 and the links A, B and C will take the positions shown by the dotted lines in Fig. 1. As the link C is swung upwardly, the extension 92 on the section C³ of the link will move from the position shown in full lines in Fig. 1 to the dotted line position or approximately at right angles to its initial position. This will cause the rod 90 to be pulled outwardly placing the spring 106 under tension and raising the piston 110 in the cylinder 94. As the piston is raised, the fluid in the cylinder will pass downwardly through the passage 114 and also through the groove 125 to the portion of the cylinder below the piston. When the

operator closes the doors, the handle 80 is released whereupon the tension spring 106 will pull the rod 90 downwardly, causing the links to move back to their initial positions. As the rod 90 and piston 110 approach their lower position, the piston will come into contact with the fluid in the cylinder and will force the fluid through the by-pass 120, the rate of flow of the fluid being determined by adjustment of the needle valve 123. Thus during the final portion of the door closing movement, the movement will be checked or cushioned thereby preventing slamming of the doors and avoiding a noisy operation thereof.

It has been found desirable to provide means whereby the elevator car circuit is opened when the hatchway doors are opened and is closed, permitting the operation of the car, only when the doors are closed. In the present instance this is accomplished by means of a link 150 pivoted to the extension 92 on the section C³ of the link C and pivotally connected at its upper end to a bar 151 which in turn has secured thereto a blade 152 of a knife switch. This blade completes the circuit through the switch contacts 153 when the link C is in door closing position but is swung upwardly as shown on the dotted lines in Fig. 1 away from the contacts 153 when the door is open.

From the foregoing description it will be seen that simple, practical and effective means has been designed for accomplishing the objects of the invention. By means of the various adjustments a standard outfit can be manufactured and applied to doors of various sizes and dimensions. Furthermore, the adjustments described permit the accurate mounting of the device when installed and facilitate the proper alignment and thereby eliminate all unnecessary friction. The use of the tension spring as described is particularly desirable since compression springs have a tendency to get out of alignment and rub against the spring housing. Moreover, when the tension spring is expanded it tends to decrease its diameter instead of increase as is the case with a compression spring. Attention is also again directed to the cushioning means and to the particular features pointed out whereby the leakage of oil is eliminated and the proper functioning of the device is insured.

Although the door illustrated in the drawings has two sliding sections, it will be understood that, if desired, a single sliding section or more than two sliding sections may be used, without change in the operating mechanism, except as to the number of links used.

Although one specific embodiment of the invention has been particularly shown and described, it will be understood that the invention is capable of modification and that

changes in the arrangement and in the construction of the various cooperating parts may be made without departing from the spirit or scope of the invention as expressed in the following claims.

5. What I claim is:

1. Door check or cushioning mechanism comprising a rod, a piston connected thereto, a cylinder receiving said piston and adapted 10 to be connected to a fixed abutment, a bypass through the cylinder wall and communicating with the lower end of the cylinder through a lateral opening therein, the bottom of said piston being beveled.
- 15 2. Door cushioning mechanism comprising a cylinder, a rod extending into said cylinder and having a piston thereon, a fluid bypass through the cylinder wall for conducting fluid from the space in the cylinder 20 below the piston to the space above the piston when the piston is disposed in the lower end portion of the cylinder and a chamber surrounding the rod and communicating at one end with the cylinder at one side of the rod 25 and having an air vent located on the opposite side of the rod and at the opposite end of the chamber.
3. Door actuating and checking mechanism comprising a rod operatively connected 30 to the door, hydraulic checking mechanism operated by said rod, a tension spring, connected to said rod and to a fixed abutment and encircling said hydraulic checking mechanism, for closing the door and a casing 35 surrounding said spring.
4. Door actuating mechanism comprising a rod operatively connected to the door, a member connected to a fixed abutment, a tension spring connected to said abutment and 40 to said rod, a casing surrounding said spring

and spaced therefrom, the connection between the rod and spring being constructed to center the spring and to prevent contact between the casing and spring, said rod being 45 slideable.

5. Door closing and checking mechanism comprising a cylinder, a rod having a piston secured thereto and disposed in said cylinder, a spring secured to said rod and surrounding and secured to said cylinder, and 50 a casing secured to the cylinder and surrounding the spring.

6. Door closing and checking mechanism comprising a cylinder, a rod having a piston secured thereto and disposed in said cylinder, 55 a tube surrounding a portion of and secured to said rod, a spring secured to said tube and to said cylinder and surrounding the cylinder, and a casing secured to said cylinder and surrounding said spring.

7. Door closing and checking mechanism comprising a cylinder, a rod having a piston secured thereto and disposed in said cylinder, a tube surrounding a portion of and secured to said rod, and a spring secured to 60 said tube and to said cylinder and surrounding the cylinder, said tube being adjustably connected to said rod whereby the tension of the spring can be regulated.

8. Door closing and checking mechanism 70 comprising a cylinder, a rod having a piston secured thereto and disposed in said cylinder, a collar surrounding and secured to said cylinder, a spring secured to said rod and to said collar, and a casing surrounding said 75 spring and secured to said collar, said rod being slideable through one end of the casing.

In witness whereof, I have hereunto set my hand this 10th day of February, 1923.

THOMAS BRADY
